DESIGN FOR A REFRIGERATOR CABINET

Harold Van Doren, Ardmore, and Robert A. May,
Wynnewood, Pa., assignors to Philco Corporation,
Philadelphia, Pa., a corporation of Pennsylvania

Application February 26, 1949, Serial No. 1,098

Term of patent 3½ years

(Cl. D67—3)

To all whom it may concern:

Be it known that we, Harold Van Doren and Robert A. May, citizens of the United States, residing, respectively, at Ardmore, in the county of Montgomery and State of Pennsylvania, and at Wynnewood, in the county of Montgomery and State of Pennsylvania, have invented a new, original, and ornamental Design for a Refrigerator Cabinet, of which the following is a specification, reference being had to the accompanying drawing, forming part thereof, in which:

Figure 1 is a view, in perspective, of a refrigerator cabinet in open position, showing our new design;

Figure 2 is a fragmentary, sectional view taken along the line 2—2 of Figure 1; and

Figure 3 is a fragmentary, sectional view taken along the line 3—3 of Figure 1.

The dominant features of our design reside in the portions shown in full lines.

The side of the cabinet not illustrated in the drawing is substantially plain and similar to the side shown.

We claim:

The ornamental design for a refrigerator cabinet, substantially as shown and described.

HAROLD VAN DOREN.
ROBERT A. MAY.
